UNITED STATES PATENT OFFICE.

WILLIAM BARTHOLOMEW, OF CHICAGO, ILLINOIS, ASSIGNOR TO TROY LAUNDRY
MANUFACTURING COMPANY, A CORPORATION OF NEW YORK.

SAFETY MECHANISM FOR IRONING-MACHINES.

1,346,872.

Specification of Letters Patent. Patented July 20, 1920.

Application filed December 10, 1914. Serial No. 876,534.

To all whom it may concern:

Be it known that I, WILLIAM BARTHOLOMEW, a citizen of the United States, residing at Chicago, in the county of Cook and State 5 of Illinois, have invented certain new and useful Improvements in Safety Mechanism for Ironing-Machines, of which the following is a specification.

My invention relates in general to safety mechanism for protecting the operators of 10 machines, and more particularly to safety mechanism for cylinder ironing machines to automatically stop the operation of such machines should the hands of the operators approach dangerous position.

In the operation of ironing machines comprising steam-heating cylinders and coöperating rolls between which the articles are carried, an operator in feeding the articles 20 between the receiving roll and cylinder sometimes carelessly allows his or her hands to be caught and crushed while endeavoring to straighten or properly arrange an article passing into the machine. It also sometimes 25 occurs that articles become disarranged while passing through the machine and the operator, in reaching above the rolls at the delivery side of the machine to disengage the articles, has his hand severely injured.

The primary object of my invention is to 30 provide safety mechanism for ironing, and similar machines, which will protect the operators from injury by automatically stopping the machines when the hands of the operators are in dangerous proximity either 35 to the feeding or receiving sides of the machines.

A further object of my invention is to 40 provide means for stopping the operation of a machine, which will be actuated by any one of a plurality of safety guards located at different exposed portions of the machine.

A still further object of my invention is 45 to provide a safety guard for machines which will automatically stop the machine when moved in either direction by the engagement therewith of the hands or other portions of the body of an operator.

50 A still further object of my invention is to provide safety mechanism for protecting from injury the operators of machines

which will be simple in construction, convenient in arrangement, and efficient in use.

My invention will be more fully disclosed 55 hereinafter with reference to the accompanying drawings, in which the same is illustrated as embodied in a convenient and practical form, and, in which,—

Figure 1 is an end elevation in section of 60 a cylinder ironing machine equipped with my improved safety mechanism, and,

Fig. 2 is a perspective view of the safety mechanism disconnected from the machine.

Similar reference characters are used to 65 designate similar parts in two figures of the drawings.

Reference letter A indicates one of the side supporting frames of a cylinder ironing machine. B¹ and B² indicate the trunnions at the ends of the steam-heated cylinders which are rotatably mounted between the side frames. Reference characters C¹—C²—C³—C⁴ and C⁵ indicate the bearings for 70 rolls which coöperate with the upper steam cylinder. Reference characters D¹—D²—D³—D⁴ and D⁵ designate fluid pressure cylinders, having therein pistons connected 75 with the respective bearings C¹—C²—C³—C⁴ and C⁵ to raise and lower such bearings, 80 and thereby move the rolls supported by them into and out of operative relation with the adjacent steam cylinder. E designates the feed apron upon which the articles are placed and by which they are carried between the first roll and the upper cylinder. F designates the delivery apron located at 85 the opposite side of the machine from the feed apron E, and upon which the articles are received from the machine and conveyed 90 to a position where they may be removed by the operator.

Inasmuch as my invention is not restricted in its application to a cylinder ironing machine of the type partially illustrated in 95 Fig. 1, it is not necessary to a full understanding of my invention that such machine should be illustrated and described in detail. It will be understood that my invention is not limited in its use to ironing machines 100 of any particular construction, nor in fact to ironing machines, but is capable of use in connection with other machines.

G designates a lever for controlling the

starting and stopping of the machine through the medium of any suitable mechanism for connecting and disconnecting a source of power with the moving parts of the machine. Inasmuch as my invention is not concerned with the particular mechanism actuated by the starting lever G for effecting the starting and stopping of the machine, it is not necessary to a full disclosure of my invention that such mechanism should be illustrated or described.

H designates a safety guard of any suitable construction, such for instance as a rectangular panel formed of a surrounding frame supporting wire fabric. The guard H is mounted upon the machine in front of the space between the receiving roll and coöperating steam cylinder, and is of a length conforming to the width of the feed apron E, in order that all portions of the articles fed to the machine by the apron must pass below the guard. The guard is provided with trunnions h^1 and h^2 , which are supported in bearings formed in the upper ends of the brackets H^1 and H^2 secured to the end frames of the machine. One of the trunnions, as for instance h^2 , has fixed thereon a crank arm h connected at its outer end by means of a link h with the swinging end of a short lever K, the latter being fulcrumed at k^1 upon the adjacent side of the frame of the machine. The lever K has projecting therefrom a rod L, upon which rests a bar M, the latter being connected at one end through an offset portion m with the controlling lever G of the machine. A flexible connection n extends from the bar M to a weight N, the latter being preferably located within a cylindrical guide casing O. The flexible connection n passes through a curved tubular guide o to the interior of the cylinder O, where it is connected with the weight N. The weight N tends to move the bar M in a direction to oscillate the lever G in a direction to stop the operation of the machine.

In order that the lever G may be retained against the action of the weight N in the position which it must assume in order that the machine may be operated, a notch p is formed in the under-surface of the bar M which engages a post P fixed to and projecting outwardly from the adjacent side frame of the machine. In order that the bar M may be retained in proper position upon the supporting pin L, a guide loop l is secured to the pin L and extends around the bar M.

R designates a second safety guard which may be conveniently of the same construction as the guard H. The guard R is located at the delivery side of the machine above the apron F, and in position to be engaged by an operator attempting to reach the adjacent rolls and cylinder of the machine. The guard R is provided with laterally project-

ing trunnions r^1 and r^2 intermediate of its upper and lower edges, and which are mounted in bearings formed in the upper ends of brackets R^1 and R^2 , fixed upon the adjacent portions of the side supporting frames of the machine.

Rods S^1 and S^2 are connected to the top of the guard R and pass through openings in the top of the frame of the guard H. Collars s^1-s^2 are fixed upon the rods S^1-S^2 adjacent the inner surfaces of the frame of the guard H, so that an inward movement of the top of the guard R will oscillate inwardly the lower portion of the guard H.

In order that the operation of the machine may be conveniently stopped, when desired, by an operator at the delivery side of the machine, rods T^1 and T^2 are connected to the opposite sides of the guard H adjacent its bottom, as by means of the brackets t . The rods T^1 and T^2 pass through guide brackets T, supported upon the side frames of the machine. The free ends of the rods T^1 and T^2 are provided with knobs t^1 and t^2 , respectively, by means of which either of the rods may be pulled in a direction away from the guard H, and the latter thereby oscillated to stop the operation of the machine in a manner hereinafter to be more fully described.

Fixed upon each of the side frames of the machine adjacent the lower edge of the guard R, is a bracket U, upon which is fulcrumed intermediate of its ends a short-lever u. The levers u are provided with slots through which extend the rods T^1 and T^2 , respectively, such rods having fixed thereon collars u^1 and u^2 in positions to be engaged by the respective levers u when the latter are oscillated. Projecting laterally from the sides of the guard R, adjacent its bottom, are brackets v^1 and v^2 , overlying the portions of the short-levers u which depend below their fulcrums.

The operation of my improved safety mechanism is as follows: Should the hand of an operator in arranging articles upon the feed apron E approach too close to the adjacent roll and cylinder, it will engage the bottom of the guard H and move the same inwardly toward the machine. Such movement of the guard oscillates its trunnions so that the crank-arm h will be raised and will lift upwardly the depending rod h, which in turn will oscillate the lever K. The upward oscillation of the lever K lifts the bar M so that the notch p therein will be disengaged from the post P, thereby permitting the weight N to fall and oscillate the controlling lever G into position to discontinue the operation of the machine.

After the pressure upon the guard has been discontinued, it oscillates by gravity to its normal position in which the bar M rests upon the post P. The machine may then be

again started by moving the lever G toward the machine, and when it has reached the desired position the notch p in the bar M will have engaged the post P so as to prevent 5 the weight from moving the lever G into position to stop the operation of the machine.

When for any reason an operator on the delivery side of the machine desires to stop 10 its operation, as for instance to disengage articles which may have become tangled, it is merely necessary for the operator to exert a pull upon either of the knobs t^1 or t^2 , on the rod T^1 or T^2 , which oscillates the 15 bottom of the guard H toward the machine and thereby trips the bar M and permits the weight to move the controlling lever G to its off position.

Should an operator on the delivery side 20 of the machine attempt while the machine is in operation to reach articles passing through the machine, the top of the guard R will be oscillated inwardly through the necessary contact therewith of the operator. 25 Such oscillation of the guard R oscillates the top of the guard H away from the machine through the medium of the rods S^1 and S^2 and the collars s^1 and s^2 thereon. The machine is consequently stopped. The machine 30 is also instantly stopped should the bottom of the guard R be moved inwardly, inasmuch as such movement of the guard causes the brackets v^1 and v^2 thereon to oscillate the levers u and cause them to engage the 35 collars u^1 and u^2 fixed upon the rods T^1 and T^2 and move the latter in a direction to oscillate inwardly the bottom of the guard H.

From the foregoing description it will be observed that I have invented an improved 40 safety mechanism comprising guards located at a plurality of places upon the machine so that should any of the guards be moved, the operation of the machine will be discontinued and danger of injury to the 45 operators avoided. It will be further observed that in my improved safety mechanism the machine is stopped when a guard is moved in either direction, thereby protecting from injury an operator who might 50 attempt to reach either above or below the safety guard.

While I have described more or less in detail the specific embodiment of my invention herein disclosed, yet it will be understood 55 that I do not intend to be limited thereto, as I comprehend changes in form, the proportion of parts, and the substitution of equivalents, as occasion may require, or as may be expedient. It will be further understood 60 that my invention is not limited in its application to the type of ironing machine in connection with which it is illustrated, but is capable of application to various machines.

I claim:—

1. The combination with a machine having moving parts exposed at a plurality of places, of a device for controlling the operation of the machine, a safety guard for protecting each of the exposed places of the machine, means operatively connecting said safety guards with said device to actuate the same to stop the operation of the machine when any of said guards is moved and means extending from said guard to a remote part of the machine for manually moving the guard to actuate said device to stop the operation of the machine. 75

2. The combination with a machine comprising moving parts between which articles are passed, of a safety guard protecting the side of the machine where the articles are fed to it, a safety guard pivotally supported upon a horizontal axis intermediate of its top and bottom for protecting the side of the machine from which the articles are delivered, a device for controlling the operation of the machine, and means operatively connecting both of said safety guards with said device for actuating the same to stop 85 the operation of the machine when said first guard is moved in one direction and when said second guard is moved in either direction. 90

3. The combination with a machine having moving parts exposed at a plurality of places, of a device for controlling the operation of the machine, a plurality of oscillating guards protecting different exposed portions of the machine, means operatively connecting one of said guards with said device for actuating the same to stop the operation of the machine, rods connecting the said guards so that the movement of any of said guards will effect the stopping of the machine, and means extending from said guards for manual operation to effect the stopping of the machine. 95 100

4. The combination with a machine having moving parts exposed at a plurality of places, of a device for controlling the operation of the machine, a pair of safety guards each oscillatory upon horizontal axes located at different exposed portions of the machine, rods connecting the tops of the 110 guards, means connecting one of said guards with said device for actuating the same to stop the operation of the machine, rods extending from the bottom of said last-mentioned guard to positions adjacent the bottom of said other guard, and means operatively connecting said latter guard with said last-mentioned rods to effect the stopping of the machine when the bottom of said last-mentioned guard is oscillated toward the machine. 115 120 125

5. The combination with a machine comprising exposed moving parts, of a movable

safety guard for protecting said moving parts, and a device controlling the operation of the machine actuated by a movement of said guard in either direction to stop the 5 operation of the machine.

6. The combination with a machine comprising exposed moving parts, of a safety guard for protecting said moving parts, means for pivotally supporting said guard 10 to oscillate upon a horizontal axis intermediate of its top and bottom, and a device

controlling the operation of the machine actuated by a movement either of the top or bottom of said guard toward the machine to stop the operation of the machine. 15

In testimony whereof I have subscribed my name.

WILLIAM BARTHOLOMEW.
